DESIGN FOR A CORNER CUPBOARD

Dwight J. Baum, New York, N. Y., assignor to Curtis Companies Incorporated, Clinton, Iowa,
a corporation of Iowa

Application October 18, 1937, Serial No. 72,273

Term of patent 7 years

To all whom it may concern:

Be it known that I, Dwight J. Baum, a citizen of the United States and a resident of New York, in the county of Bronx and State of New York, have invented a new, original, and ornamental Design for a Corner Cupboard, of which the following is a specification reference being had to the accompanying drawing, forming part thereof.

Figures 2 and 3 are vertical sectional views on lines 2—2 and 3—3, respectively, of Figure 1, Figure 3 being a continuation of Figure 2; and

I claim:

The ornamental design for a corner cupboard, substantially as shown and described.

DWIGHT J. BAUM.
